UNITED STATES PATENT OFFICE.

WILLIAM T. ABBOTT, OF BIRMINGHAM, ALABAMA, ASSIGNOR OF ONE-HALF TO D. E. HENSLEY, OF BIRMINGHAM, ALABAMA.

DESIGN FOR A BADGE OR SIMILAR ARTICLE.

Application filed March 10, 1926. Serial No. 16,853. Term of patent 3½ years.

To all whom it may concern:

Be it known that I, WILLIAM T. ABBOTT, a citizen of the United States, residing at Birmingham, in the county of Jefferson and State of Alabama, have invented a new, original, and ornamental Design for a Badge or Similar Article, of which the following is a specification, reference being had to the accompanying drawings, forming a part hereof.

In the drawings:

I claim:

The ornamental design for a badge or similar article, as shown.

WILLIAM T. ABBOTT.
